(57) **CLAIM**

The ornamental design for a holster with accessory receiving holes, as shown and described.

DESCRIPTION

FIG. 1 is a first perspective view of the holster with accessory receiving holes;

FIG. 2 is a left side elevational view of the holster with accessory receiving holes;

FIG. 3 is a right side elevational view of the holster with accessory receiving holes;

FIG. 4 is a top plan view of the holster with accessory receiving holes;

FIG. 5 is a bottom plan view of the holster with accessory receiving holes;

FIG. 6 is a front elevational view of the holster with accessory receiving holes;

FIG. 7 is a back elevational view of the holster with accessory receiving holes;

FIG. 8 is a second perspective view of the holster with accessory receiving holes with a firearm inserted therein;

FIG. 9 is a third perspective view of the holster with accessory receiving holes with a belt clip and a claw device attached thereto; and,

FIG. 10 is a fourth perspective view of the holster with accessory receiving holes with a firearm inserted therein and a retention strap attached thereto.

The claw device, the firearm, the retention strap, and the belt clip are shown with broken lines to provide an exemplary environment of the claimed design and form no part of the claimed design.

The broken lines defining the holster show the boundary of the claim and form no part of the claimed design.
